(57) **CLAIM**

The ornamental design for a threaded tumbler bottle cap with ice filter, as shown and described.

DESCRIPTION

FIG. 1 is an exploded top-left-front perspective view of a threaded tumbler bottle cap with ice filter showing my design;

FIG. 2 is a bottom-right-rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right-side elevational view thereof;

FIG. 8 is a left-side elevational view thereof;

FIG. 9 is an enlarged top-left-front perspective view thereof, wherein the threaded tumbler bottle cap with ice filter is shown in a collapsed configuration; and,

FIG. 10 is an enlarged bottom-right-rear perspective view thereof, wherein the threaded tumbler bottle cap with ice filter is shown in the collapsed configuration.
